HIRAM NEWTON BERRY, OF GREENVILLE, MISSISSIPPI, ASSIGNOR, BY DIRECT AND MESNE ASSIGNMENTS, TO COTTON HARVESTER CORPORATION OF AMERICA, OF GREENVILLE, MISSISSIPPI, A CORPORATION OF DELAWARE

COTTON PICKER

Application filed April 22, 1927. Serial No. 185,826.

This invention relates to improvements in cotton pickers, and consists of the combinations, constructions and arrangements herein described and claimed.

5 The primary object of this invention is to provide such improvements in cotton picking machinery as will insure thorough and effective engagement of the picking elements, especially those of the revolving spindle or 10 needle type, with the ripened bolls in use, resulting in the picking of cotton in a cleaner condition, and in greater quantities, than is now possible.

15 Other objects and advantages appear in the following specification, reference being had to the accompanying drawings, in which,

Figure 1 is a horizontal section of the cylinder of a cotton picking machine illustrating the application of the improvement.

20 Figure 2 is a detail vertical section of the upper portion of the cylinder.

Figure 3 is a detail perspective view of one 25 half of the cylinder in Figure 1, only a few of the revolving needles and stationary elements being shown.

Figure 4 is a detail section showing how the stationary elements are mounted upon the cylinder.

30 Figure 5 is a detail sectional view of the upper portion of the cylinder showing a modified mode of driving the vertical shafts for revolving the picker spindles.

Figure 6 is a detail sectional view illustrating the unitary construction of the pulley and 35 spur gear.

Figure 7 is a detail plan view illustrating the disposition of the drive pulley in reference to the foregoing vertical drive shaft in the modified construction.

40 As briefly indicated in the foregoing statement of the object of the invention, the improvement herein disclosed relates particularly to that type of cotton picking machinery in which revolving spindles or needles

45 are employed for the purpose of abstracting the cotton from the bolls, to which end the invention is an improvement specifically on the cotton picker disclosed in my co-pending application for Letters Patent filed August 3, 1925, Serial No. 47,917.

Inasmuch as the aforesaid application discloses structure not concerned with the present improvement, only such parts of the machine as are directly concerned with the invention are herein shown. Such parts are 55 briefly described as follows:

The cylinder or movable drum 58 (of which there are two in the particular machine involved) comprises two semi-cylindrical sections which are joined in any suitable 60 manner to arrive at the construction well shown in Figure 1. One of the semi-cylindrical sections is shown in Figure 3. The cylinder 58 has top and bottom plates, the top plate 60 being the only one herein shown. 65

An upright supporting post 62, fixedly secured upon the machine in any suitable manner, provides the mounting upon which the cylinder is revolvably applied. An anti-friction bearing 63, disposed between the top 70 plate 60 and a hub upon the supporting post, carries much of the weight of the cylinder, there being (in practice) a somewhat similar thrust bearing at the bottom of the supporting post. 75

A plurality of vertical shafts 70, arranged in an annular series, has bearing in the top and bottom plates of the cylinder 58, and inasmuch as the cylinder revolves upon the supporting post 62 it follows that the shafts 80 70 move around with the cylinder. Each of the shafts 70 has a plurality of beveled gears 71.

These gears 71 mesh with beveled gears 76 upon the inner ends of certain vertical series 85 of a plurality of vertical series of picking spindles 57 radiating from and arranged circumferentially of the cylinders 58. The beveled gears 76 have associated gears 75 which mesh with and drive similar gears on the two vertical series of picker spindles on the adjacent sides of the particular vertical series concerned. 90

In other words, there are ten of the vertical shafts 70 which, for the purpose of description, are herein known as the drive shafts, while there are thirty vertical rows or series of the picker spindles. This makes it necessary that one of the vertical shafts 70 must 100

drive three vertical rows or series of the spindles, and the driving is accomplished by means of the gearing just described. It is deemed unnecessary to describe the details of the picker spindles because these are fully brought out in the application mentioned, it being only necessary to bear in mind that the vertical shafts 70 drive or rotate the picker spindles by the gearing illustrated as the cylinder 58 revolves upon its vertical axis.

At the upper ends of the shaft 70 above the top plate 60 are secured pulleys 72, and these pulleys form part of the driving connections of the picking spindles. According to the foregoing application, those pulleys 72 of a predetermined number of driving shafts 70 and associated picking spindles, come into engagement with the driving belt as such pulleys move around into range of a driving belt (not shown) when the picking spindles enter the zone of the cotton plants. It is thus that rotation is imparted to the picking spindles only when needed.

The invention comprises the provision of spurs or fingers 77 which may be of substantially equal length to the picking spindles 57. But unlike the picking spindles, the spurs 77 are stationarily mounted, for which purpose they are provided with threaded ends 78 (Figure 4) with adjacent nut-like formations 79 by which they can be screwed in place in the cylinder wall. The purpose of the spurs or fingers 77 is to facilitate and make positive the introduction of the cotton to the revolving picker spindles 57. This is readily understood upon reference to Figure 1. It is a principle of the machine that the rate of bodily forward motion of the machine in the direction of arrow 80 is the same as the rearward motion of the extremities of the picker spindles in the direction of arrow 81. The effect of this is to merely introduce the picking spindle into the cotton plant and to withdraw it therefrom with so little disturbance as not to harm the plant.

Should it so happen that an open boll 82 comes between an adjacent pair of picking spindles 57 it is evident that the machine will pass by with little likelihood of the revolving picking spindles reaching the cotton and removing it from the plant. It is here that the function of the spurs 77 appears. These spurs, although located in any desired relationship to the picking spindles, are preferably located midway between vertical and horizontal rows of the picking spindles, as plainly shown in Figure 1. The picking spindle approaching the podded boll 82 will serve to push the boll either to one side or the other, as shown in full lines at 83, the stem of the boll being flexible enough to permit this. It thus follows that the boll is pushed either against one or the other of the adjacent revolving picking spindles so that instead of passing the particular boll by the machine operates to re-

move such boll. The effectiveness of the machine is thus increased considerably.

It is desired to make it plain that the use of the relatively stationary spurs or fingers 77 is not confined to a drum or cylinder construction of cotton picker as herein disclosed but may be employed with other types of needle or spindle pickers equally as well. It is also to be understood that the cross sectional shape of these spurs may be other than round, and it has already been stated that the position of the spurs in respect to the revolving spindles or needles may be varied as is found necessary in practice.

Variation or modification of the mode of driving the shafts 70 is illustrated in Figures 5 to 7 inclusive. This modification comprises the substitution of a gear 84 for the pulley 72 upon the drive shaft 70. The drive shaft may now be cut off short close to the gear 84. A vertical stub shaft 85 is screwed into the top plate or drum head 60, the non-circular enlargement or hub 86 serving both as a nut by means of which the stub shaft may be screwed into place as well as a post upon which the combined pulley 87 and pinion 88 may revolve.

It is evident from Figure 7 that the stub shaft 85 may be placed in any desired radial location in reference to the drive shaft 70 so long as the gears are kept in mesh thereby making it possible to use larger pulleys than is possible when the pulleys are mounted directly upon the drive shaft. The use of gearing also permits of the increase of driving force delivered to the vertical shafts 70 by virtue of the increased amount of frictional contact of the belt with the pulleys, it being deemed important to observe that any diminution in speed of rotation of the vertical shafts can be compensated for by increasing the speed of the belt.

Reference is next made to a special construction of the top plate or drum head 60 as well as a special construction in the supporting post 62. The latter has a bore 89 into which a lubricant is pumped or otherwise introduced. This bore has a lateral duct 90 which discharges into a circular well 91 formed in the top plate 60. A cover plate 92, secured to the top plate 60 as at 93, covers the well in such a manner as to exclude foreign matter from the lubricant. The cover plate includes a relatively large sleeve or hub 94 which extends outwardly in spaced relationship to the post 62, and receives a covering washer 95 which may be held in place in any suitable manner.

The holes 96, through which the drive shafts 70 extend are sufficiently over sized not to interfere with the shafts. The cover plate is circularly grooved on the under side as at 97, the groove being of sufficient lateral extent as to afford communication between the well 91 and the bearings 98 of the drive

shafts. Assuming the level of the lubricant to be above the groove it follows that there will be a continuous supply of lubricant to the bearings 98, the additional effect being 5 to lubricate the various pinions 71 on the drive shafts by virtue of the lubricant running down.

While the construction and arrangement includes cotton picking machines of a generally preferred form, obviously modifications and changes may be made without departing from the spirit of the invention or the scope of the claims.

What I claim is:

- 15 1. In a cotton picker having picking elements arranged for introduction into and retraction from the plants as the cotton picker progresses along a row; in combination, means interspersed between said picking 20 elements for deflecting ripened bolls otherwise out of range of said elements into proximity with adjacent picking elements.
- 25 2. In a cotton picker having spaced picking elements in vertical and horizontal rows arranged for introduction into and retraction from the cotton plants as the picker progresses along a row: in combination, means disposed in predetermined locations in reference to said picking elements and in the spaces there- 30 between to deflect ripened bolls otherwise out of range of the picking elements into prox- imity with adjacent picking elements as said elements are introduced into the plants.
- 35 3. In a cotton picker having revoluble picking spindles arranged for introduction into and retraction from the cotton plants as the picker progresses along a row, means which is part of the picker upon which the spindles are revolvably mounted: in combination, 40 spurs mounted upon said means and being relatively stationarily located in respect to said revoluble picking spindles to move into proximity with adjacent revoluble picking spindles ripened bolls otherwise out of range 45 of said spindles.
- 50 4. In a cotton picker having a drum which is movable during a cotton picking operation, picking spindles in spaced relationship to each other revolvably mounted upon the drum and radiating therefrom, said spindles being arranged for introduction into and retraction from the cotton plants as the drum moves along a row: in combination, spurs supported in predetermined spaced relationship to the 55 picking spindles to move toward adjacent spindles ripened bolls otherwise out of range of said spindles, and means by which said spurs are fixed in position upon the drum and in relationship to the revoluble spindles.
- 60 5. A cotton picker comprising the combination of a plurality of picking spindles, a drum upon which said spindles are mounted in spaced and radiating positions, means for moving the drum as the cotton picker progresses along a row thereby to introduce the

spindles into and retract them from the plants, means to impart rotation to the spindles during the period of introduction there- 70 of into the plants thereby to remove ripened bolls, spurs in predetermined spaced relation- ship to the picking spindles and in radiating positions upon the drum to move into contact with adjacent spindles ripened bolls other- wise out of range of said spindles, and means by which said spurs are fixed in position upon 75 the drum.
